The ornamental design for a hexagonal-shaped jewelry box, as shown and described.

DESCRIPTION

FIG. 1 is a perspective view of an assembled hexagonal-shaped jewelry box;

FIG. 2 is a front view of the hexagonal-shaped jewelry box shown in FIG. 1;

FIG. 3 is a back view of the hexagonal-shaped jewelry box shown in FIG. 1;

FIG. 4 is a left side view of the hexagonal-shaped jewelry box shown in FIG. 1;

FIG. 5 is a right side view of the hexagonal-shaped jewelry box shown in FIG. 1;

FIG. 6 is a top view of the hexagonal-shaped jewelry box shown in FIG. 1;

FIG. 7 is a bottom view of the hexagonal-shaped jewelry box shown in FIG. 1;

FIG. 8 is a perspective view of the hexagonal-shaped jewelry box of FIG. 1 in an unassembled outline configuration, including fold lines represented by thin lines;

FIG. 9 is a front view of the hexagonal-shaped jewelry box shown in FIG. 8;

FIG. 10 is a back view of the hexagonal-shaped jewelry box shown in FIG. 8;

FIG. 11 is a right side view of the hexagonal-shaped jewelry box shown in FIG. 8;

FIG. 12 is a left side view of the hexagonal-shaped jewelry box shown in FIG. 8;

FIG. 13 is a top view of the hexagonal-shaped jewelry box shown in FIG. 8;

FIG. 14 is a bottom view of the hexagonal-shaped jewelry box shown in FIG. 8;

FIG. 15 is a perspective view of an additional embodiment of an assembled hexagonal-shaped jewelry box;

FIG. 16 is a front view of the hexagonal-shaped jewelry box shown in FIG. 15;

FIG. 17 is a back view of the hexagonal-shaped jewelry box shown in FIG. 15;

FIG. 18 is a left side view of the hexagonal-shaped jewelry box shown in FIG. 15;

FIG. 19 is a right side view of the hexagonal-shaped jewelry box shown in FIG. 15;

FIG. 20 is a top view of the hexagonal-shaped jewelry box shown in FIG. 15;

FIG. 21 is a bottom view of the hexagonal-shaped jewelry box shown in FIG. 15;

FIG. 22 is a perspective view of the hexagonal-shaped jewelry box of FIG. 15 in an unassembled outline configuration, including fold lines represented by thin lines;

FIG. 23 is a front view of the hexagonal-shaped jewelry box shown in FIG. 22;

FIG. 24 is a back view of the hexagonal-shaped jewelry box shown in FIG. 22;

FIG. 25 is a right side view of the hexagonal-shaped jewelry box shown in FIG. 22;

FIG. 26 is a left side view of the hexagonal-shaped jewelry box shown in FIG. 22;

FIG. 27 is a top view of the hexagonal-shaped jewelry box shown in FIG. 22; and,

FIG. 28 is a bottom view of the hexagonal-shaped jewelry box shown in FIG. 22.

The broken lines shown in the drawings illustrate portions of the hexagonal-shaped jewelry box that form no part of the claimed design.
